PRESSURE OPERATED SUBSURFACE WELL APPARATUS

Martin B. Conrad, Huntington Park, Calif., assignor to Baker Oil Tools, Inc., Vernon, Calif., a corporation of California

Application September 26, 1949, Serial No. 117,877

18 Claims. (Cl. 166—63)

1

The present invention relates to well apparatus positionable in a well bore, and more particularly to apparatus capable of utilizing a motivating fluid or gaseous force developed at the location of the apparatus in the well bore. In a more limited sense, the invention pertains to tools for running and setting well packers in well bores.

An object of the invention is generally to improve subsurface pressure developing devices for operating well equipment in well bores.

Another object of the invention is to provide an apparatus for developing a fluid or gaseous force in the well bore, for the purpose of operating well equipment therein, in which the apparatus can be made of a small diameter for the same effective total force produced, and also substantially shorter in length.

A further object of the invention is to provide an apparatus for developing a fluid force in a well bore, in which the effect of the hydrostatic head of fluid in the well bore is counterbalanced, preferably completely, allowing all of the fluid force developed in the apparatus to be available for the operation of well equipment attached thereto.

Yet another object of the invention is to provide improved means for retarding the expansion of gas under pressure developed in subsurface well apparatus.

This invention possesses many other advantages, and has other objects which may be made more clearly apparent from a consideration of a form in which it may be embodied. This form is shown in the drawings accompanying and forming part of the present specification. It will now be described in detail, for the purpose of illustrating the general principles of the invention; but it is to be understood that such detailed description is not to be taken in a limiting sense, since the scope of the invention is best defined by the appended claims.

Referring to the drawings:

Figs. 1 and 1a together constitute a longitudinal section through well equipment disposed in a well casing, Fig. 1a constituting a lower continuation of Fig. 1;

Fig. 2 is a view similar to Fig. 1a, illustrating the apparatus partially operated in the well casing;

Fig. 3 is a view similar to Fig. 1a, illustrating the apparatus more fully operated in the well casing;

Fig. 4 is a cross-section taken along the line 4—4 on Fig. 3;

Fig. 5 is a cross-section taken along the line 5—5 on Fig. 3;

2

Fig. 6 is a cross-section taken along the line 6—6 on Fig. 1a;

Fig. 7 is a cross-section taken along the line 7—7 on Fig. 3.

5 The setting or operating tool A, disclosed in the drawings, is secured to the lower end of a wire line or cable B, which may have a central electrically conductive core C. The setting tool may be connected to a well packer D, that is to be set in packed-off condition within a well casing E.

10 Although described in connection with the specific well packer illustrated in the drawings, it is to be understood that the setting or operating apparatus A can be used in conjunction with other specific well packers, and in the operation of other subsurface well equipment.

15 The well packer D includes an elongate central packer body 10 having a lower guide and abutment 11 threaded, or otherwise attached, to its lower end, and an upper abutment 12 movably mounted upon its upper portion. A lower, circumferentially continuous slip sleeve 13 rests upon the lower abutment 11 and surrounds the upwardly projecting central boss 14 of the latter. This slip sleeve 13 is provided with an inner inclined surface 15 tapering upwardly and outwardly for cooperation with a companion tapered surface 16 on a lower frusto-conical expander 17 slidable along the body 10.

20 25 30 The well packer D includes an elongate central packer body 10 having a lower guide and abutment 11 threaded, or otherwise attached, to its lower end, and an upper abutment 12 movably mounted upon its upper portion. A lower, circumferentially continuous slip sleeve 13 rests upon the lower abutment 11 and surrounds the upwardly projecting central boss 14 of the latter. This slip sleeve 13 is provided with an inner inclined surface 15 tapering upwardly and outwardly for cooperation with a companion tapered surface 16 on a lower frusto-conical expander 17 slidable along the body 10.

A packing assembly 19, which is preferably of natural or synthetic rubber, encompasses the body and rests upon the upper end of the lower expander 17.

35 The upper end of the packing sleeve 19 engages the lower end of an upper frusto-conical expander 26, which is also slidable along the upper portion of the packer body 10, and has an upward and inwardly tapering external surface 29 cooperable with a companion internal surface 30 on the interior of a circumferentially continuous upper slip sleeve 31 which engages the upper abutment 12. The inner end of the slip sleeve 31 encompasses a centering boss 32 depending from the upper abutment.

40 It will be noted from the drawings that the upper slip sleeve 31 and the upper expander 26 are substantially identical with the corresponding parts at the lower portion of the well packer. However, the parts are oppositely arranged. In addition, it is to be noted that the upper slip sleeve 31 is provided with upwardly facing wickers or teeth 33 for embedding in the wall of the well casing E, to prevent upward movement of the well packer D therewithin. The lower slip sleeve 13 is provided with downwardly facing

45 50 55 wickers or teeth 34 for embedding in the casing

wall, to prevent downward movement of the well packer therewithin.

The well packer D is set in the well casing B by moving the upper abutment 12 in a downward direction, and the body 10 and its lower abutment 11 in an upward direction with respect to each other. Since the slip sleeves 13, 31 are initially circumferentially continuous, they are designed to break into segments upon imposition of a predetermined wedging force thereon. Thus, each slip sleeve is of relatively thin section, and has inwardly extending longitudinal ribs 35 that cooperate with an associated expander 17 or 26. Relative longitudinal movement between each slip sleeve and its associated expander will cause the sleeve to be wedged over the expander and produce a fracturing or breaking of each sleeve at its thin wall sections 36 into separate segments 37 (Fig. 7), such segments being movable along the tapered surface of the expander and outwardly into engagement with the well casing E. Originally, the slips cannot expand, in view of their circumferential continuity.

The well packer D is run in the well casing to the desired setting point, whereupon the upper abutment 12 is shifted downwardly of the body 10, to wedge the upper slip sleeve 31 (which is weaker than the lower slip sleeve 13) over the expander 26, producing fracture of the sleeve 31 into a plurality of segments 37 and their engagement with the well casing (Fig. 2). Inasmuch as these slip segments 37 are wedged between the upper expander 26 and the casing E, they cannot move downwardly to any further extent. The packer body 10 is then shifted upwardly, causing its lower guide and abutment 11 to move upwardly, carrying the lower expander 17 and lower slip ring 13 with it as a unit. During this motion, the lower expander 17 is moved toward the upper expander 26, shortening the packing sleeve 19 and expanding it outwardly into firm sealing engagement with the casing E (Fig. 3).

A continuation of the upward strain on the packer body 10 then wedges the lower slip sleeve 13 over the lower expander 17, effecting fracture of the sleeve into a plurality of separate segments, of the same general character as the upper slip segments 37, and their longitudinal upward movement along the lower expander, accompanied by their radial outward shifting into anchoring engagement with the well casing B, such as disclosed in Fig. 3.

The well packer D is retained with its slips and packing elements in their fully expanded positions by a lock device provided between the movable upper abutment 12 and the body 10. This lock device takes the form of an inherently contractible split sleeve 38 of extended length located within an inner recess 39 in the movable abutment 12. The sleeve is provided with upwardly facing annular teeth 40 on its interior engageable with the body 10, which may have a roughened exterior along its upper portion to insure digging in or biting of the ratchet teeth 40 with the body itself. The exterior of the sleeve is provided with upwardly facing annular teeth 41 engageable with companion downwardly facing teeth 42 formed in the movable abutment member.

As stated above, the well packer D is set by relative downward movement of the upper abutment 12 and upward movement of the body 10. Such relative movements can occur without interference, since the internal ratchet teeth 40 on the lock sleeve 38 merely ratchet over the cor-

responding ratchet teeth or roughened surface 43 of the body, without any substantial resistance to its movement. However, any tendency for the body 10 to move in a downward direction within 5 the upper abutment 12, or for the upper abutment to move in an upward direction with respect to the body, is prevented by the locking engagement of the internal teeth 40 of the sleeve 38 with the roughened surface or teeth 43 of the body. In effect, the ring or sleeve 38 operates as a one-way coupling or clutch element, permitting relative upward movement of the body 10, but precluding its relative downward movement. Any 15 tendency for the ring 38 to move downwardly with the body and within the upper abutment 12, is resisted by wedging of the tapered faces of its teeth 41 with the companion tapered faces forming the inclined surfaces of the buttress threads 42 in the movable abutment 12. Such wedging 20 action urges the ring 38 inwardly into the body 10 with a greater force.

As described above, the specific well packer D disclosed is set by imposing a downward force on the upper abutment 12 and an upward force on the body 10. The setting tool A enables such forces to be imparted to the parts of the well packer, to insure its complete anchoring in the well casing, and automatic detachment of the setting tool from the well packer after the latter 25 has been fully set in the well casing E.

The setting tool includes an upper cylinder 50 in which a gradually increasing pressure is developed. This cylinder includes an upper skirt 51 threadedly connected to a head 52, to which the wire line B is attached in leakproof fashion, in a known manner. The upper skirt 51 is threaded into a lower cylinder skirt 53 that has a lower head 54 threadedly secured to it. A cup-shaped piston 55 is slidable within the lower cylinder skirt 53, and may initially occupy a position adjacent and below the lower end of the upper skirt 51 (Fig. 1). This piston has piston rings 56, which may be in the form of rubber or rubber-like O rings, disposed in ring grooves 57, the piston rings slidably and sealingly engaging the wall of the cylinder skirt 53. Leakage from the cylinder 50 along the skirts 51, 53 may be prevented by providing suitable seal rings 58 in grooves 59 within the upper skirt 51 and the lower head 54 engaging the inner wall of the lower cylinder skirt 53.

The cup-shaped piston 55 is urged downwardly by generating a gas under gradually increasing pressure within a combustion chamber 60 formed in the upper skirt 51. A power charge 61, which may be a relatively slow burning combustible fuel, such as a railway flare or fusee, is disposed in the combustion chamber 60, and initially rests upon the floating piston 55. The upper end of the power charge may have the usual igniting material found in railway flares, which is exposed to enable its ignition and to initiate relatively slow burning of the power charge. Combustion 65 may be initiated by firing a cartridge 62 disposed within a gun barrel 63 threaded into the upper head 52 above the power charge 61. Leakage around the exterior of the barrel 63 is prevented by one or more suitable side seals 64 engaging the wall of the upper skirt 51 and carried within the barrel grooves 65.

Any suitable manner of firing the cartridge 62 may be employed. As disclosed specifically in the drawings, the cartridge may have a filament 66 in an electric circuit with the conductive core C

of the cable B. When the circuit through the filament is completed, it becomes incandescent and fires the powder in the cartridge 62, the flame being projected downwardly in the combustion chamber 60 and igniting the upper end of the power charge 61, which begins burning, to develop a gas within the combustion chamber at a gradually increasing pressure.

As the pressure increases in the combustion chamber, the piston 55 is urged downwardly. This downward movement is transmitted to a fluid medium in the upper cylinder 50 disposed below the piston. This medium may be predominately water 66¹ and an upper small layer of air 67, to allow for expansion and contraction of the water as a result of temperature changes before the cartridge 62 is fired. The water substantially completely fills the space in the upper cylinder 50 below the piston 55, and also extends downwardly through a passage 68 in the lower head, which passage is communicable with a central passage 69 provided in a depending rod 70, that is threadedly secured in the lower head. This rod extends through the upper head 71 of a lower cylinder 72 initially disposed adjacent the lower head 54 of the upper cylinder 50.

The lower cylinder 72 includes a cylinder sleeve 73 secured to and depending from the upper head 71, and disposed along a composite piston 74 secured to an intermediate portion of the depending rod 70. Below the composite piston, the cylinder sleeve 73 is secured to a lower cylinder head 75 that has an external flange 76 clamped between the cylinder sleeve 73 and a depending skirt 77 threadedly secured in the lower end of the sleeve 73. This skirt 77 may rest upon the upper abutment 12.

The upper and lower cylinder heads 71, 75 are provided with suitable seal rings 78 engaging the inner wall of the sleeve 73 to prevent fluid leakage through the threaded portions of the latter. The upper and lower heads 71, 75 are also slidable along the depending rod 70, leakage between the heads and rods being prevented by upper and lower seal rings 79 disposed in suitable ring grooves 80 in the heads and bearing against the periphery of the depending rod.

Initially, the lower cylinder head 75 is disposed immediately below and adjacent the composite piston 74. The lower head 75 preferably has an upwardly extending annular portion 81 engaging the piston 74 to provide a cylinder space 82 into which the water 66¹ may be forced from the passage 69 through the hollow rod 70. The water is forced through the rod passage and through a smaller passage or orifice 83, communicating with the cylinder space 82 through one or more radial ports 84, in order that the downward movement of the upper piston 55 will tend to force the liquid or water 66¹ down through the passages and ports 68, 69, 83, 84 into the cylinder space 82, urging the lower cylinder head 75 and the cylinder 72 in a downward direction. Conversely, the liquid under pressure acts upwardly over the area of the composite piston 74, tending to shift the rod 70 and the upper cylinder 50 in an upward direction.

The composite piston 74 includes an upper portion 85 threaded into a lower portion 86. These two portions are secured to the rod 70 by forming V-shaped, circumferential ribs 87 in the periphery of the rod and securing a correspondingly ribbed two-part coupling ring 88 thereto. The coupling ring 88 is first mounted on the rod 70 and the upper piston portion 85 then slid over

the rod until its threaded skirt 85a surrounds the coupling ring. Thereafter, the lower piston portion 86 may be moved upwardly from the lower end of the rod 70 to the coupling ring 88, and threaded onto the skirt portion 85a of the upper part. In this manner, the coupling ring 88 is secured between the upper and lower piston portions 85, 86 and to the rod 70, preventing longitudinal movement of the composite piston 74 with respect to the rod.

As has been stated, leakage between the rod 70 and lower cylinder head 75 is prevented by the side seal rings 79. In a similar manner, leakage between the composite piston 74 and the rod 70 may be prevented by the seal rings 90 in the upper and lower piston portions 85, 86 engaging the periphery of the rod. Leakage from the cylinder space 82 between the piston 74 and the cylinder skirt 73 is prevented by peripheral seal rings 91 disposed in ring grooves 92 and engaging the inner wall of the cylinder skirt.

In the original relative positions of the parts, the upper head 71 of the lower cylinder 72 is spaced substantially above the composite piston 74, whereas the lower head 75 of the cylinder is disposed adjacent the composite piston, but substantially above the upper abutment 12 and the upper end of the packer body 10. The well fluid is permitted to enter the annular space 93 between the sleeve 77 and rod 70 below the lower head 75 through one or more vent ports 94 provided in the sleeve. However, the annular space 95 between the upper head 71 and composite piston 74 and between the rod 70 and cylinder skirt 73 is imperforate, to prevent well fluids from leaking thereinto. This space 95 originally may contain air at atmospheric pressure.

The depending rod 70 is secured to the packer body 10 through the agency of a disruptable tension stud 97 whose opposite ends are threaded into the piston rod 70 and the body 10, respectively. The intermediate portion 98 of the tension stud is reduced in diameter to insure pulling apart of the stud at that point after the packer D has been fully set in the well casing E. When the rod 70 is secured to the tension stud 97, the sleeve 77 is engaging the upper abutment member 12.

As described above, the well packer D is anchored in the well casing E by imposing a downward force on the upper abutment 12 member and an upward force on the packer body 10, causing the slips 13, 31 and packing 19 to be expanded outwardly against the well casing. To provide this force, the cartridge 62 is fired to ignite the power charge 61, which generates gas at a gradually increasing pressure. The pressure is exerted downwardly against the cup-shaped piston 55, which transmits the pressure force to the liquid 67, 66¹ therebelow, the liquid being forced through the central passage 68, 69, 83 in the lower head 54 and rod 70, and through the ports 84 into the cylinder space 82. This liquid under pressure exerts an upward force on the piston 74 secured to the rod 70, and a downward force on the lower cylinder head 75, this downward force being transmitted through the sleeve 77 to the upper packer abutment 12.

As the pressure increases, the downward force on the upper abutment 12 becomes sufficiently great to break the upper slips 31 into segments and move them downwardly along the upper expander cone 26 and radially outward into anchoring engagement with the casing E (see Fig. 2). After this action has occurred, the wedged

upper slips tend to prevent further downward movement of the sleeve 77 and the lower cylinder 72 connected thereto. As the pressure in the combustion chamber 60 continues to increase, the pressure in the cylinder space 82 also increases at the same time, urging the piston 74 and rod 70 in an upward direction, and exerting an upward pull on the packer body 10, through the tension stud 97. This upward action shortens and compresses the packing sleeve 19 against the casing E, and then disrupts the lower slips 13 into a plurality of segments and urges them outwardly into anchoring engagement with the well casing (see Fig. 3).

As the pressure continues to increase to a further extent, as a result of the continued combustion of the power charge 61, the packer parts are urged more strongly against the casing, until the tensile strength of the reduced diameter portion 98 of the tensile stud 97 is exceeded, which pulls the stud apart at the reduced diameter portion 98 and frees the setting tool A from the well packer D. The setting tool may then be removed from the well casing E.

During the downward movement of the lower cylinder 72 along the piston 74 and rod 70, it is apparent that the upper head 71 of the lower cylinder is moved downwardly away from the lower head 54 of the upper cylinder 50. During this movement, the upper head 71 is compressing the air at atmospheric pressure located in the cylinder space 95 between the upper head 71 and the composite piston 74. The extent of compression of the air is relatively small, and, when compared with the several thousand pounds unit pressure developed in the apparatus by the power charge 61, is relatively insignificant. However, the lower cylinder head 75 need not operate against any pressure at all, during its downward movement, in view of the vent ports 94 provided through the depending sleeve, allowing any fluid in the sleeve below the head 75 to be expelled through these vent ports.

The tool is also so designed as to avoid the necessity for developing any pressure which serves no other purpose than to overcome the hydrostatic head of fluid in the well casing. This hydrostatic head of fluid acts downwardly against the entire cross-sectional annular area R of the upper head 71 of the lower cylinder. In view of the provision of the vent ports 94 in the sleeve 77, this same hydrostatic head of fluid is acting upwardly over the entire combined annular cross-section area S of the lower head 75 and cylinder skirt 77. This entire area S is equal to the area R across the upper head 71. Since the hydrostatic head of fluid is acting over equal areas and in opposite directions, its effect is counterbalanced or nullified. This enables all of the pressure developed in the setting tool A to be utilized for the purpose of setting the well packer D securely in the well casing E, and of disrupting the stud 97, to release the setting tool from the set and anchored packer.

The fact that all of the fluid pressure is utilized in the setting of the packer allows the annular area of the piston 74, and of the lower cylinder head 75, over which the fluid pressure is acting, to be made smaller, as compared with devices in which the hydrostatic head of fluid in the well casing must be overcome. The use of smaller areas enables the external diameter of the setting tool A to be made smaller, thereby allowing the setting tool to be used in well casings of smaller diameter and also allows a single

setting tool to be employed in connection with the setting of a large number of sizes of well packers D, or other well equipment.

The area of the floating piston 55 may be made greater than the internal area of the annular head 75 exposed to the liquid 66¹ in the cylinder space 82. Where this relationship exists, the cylinder 72 will be moved downwardly a greater distance than the floating piston. Thus, the lesser movement of the floating piston enables the upper cylinder 50 to be made shorter, which correspondingly reduces the length of the entire setting tool.

The relationship of the various parts, by which the lower cylinder 72 is moved downwardly and the piston 74 and rod 70 are moved upwardly also allows the entire setting tool A to be made shorter than heretofore, since the cylinder 72 acts as both a cylinder and a setting sleeve engaging the upper abutment 12. Moreover, the intermediate fluid 67, 66¹ can be forced through the orifice 83 and into the cylinder space 82. This intervening fluid, which is substantially entirely a liquid, is employed to prevent sudden expansion of the gases in the combustion chamber 60 when the tension stud 97 is released. Release of the tension stud relieves the setting tool A of its load. The ability of the water 66¹ to be transferred freely between the upper and lower cylinders 50, 72 would cause a sudden downward shifting of the floating piston 55 and of the lower cylinder 72, which would cause these parts to strike large impact blows on members disposed therebelow, with possible danger of damaging the equipment. However, the water 66¹ cannot be displaced freely between the upper and lower cylinders, since it must be forced through the relatively small orifice 83 and ports 84, which greatly retard passage of the water into the lower cylinder space 82, and, as a result, retard movement of the parts, especially after the tension stud 97 has been disrupted.

It is, accordingly, apparent that a setting or operating tool for well equipment has been provided which need not buck or offset the hydrostatic head of fluid in the well casing, which can be made of smaller diameter and of shorter length, and more economically; and which prevents sudden expansion of the gases being developed, in order to avoid damage to the equipment.

The inventor claims:

1. In operating apparatus for well devices to be located in well bores; a longitudinally extending rod; a piston secured to said rod; a cylinder adapted to be operatively associated with the well device to operate the same and including a sleeve slidable along said piston in sealing engagement therewith and also having upper and lower inwardly directed annular members secured to said sleeve on opposite sides of said piston, said members being slidable along said rod in sealing engagement therewith; means for feeding fluid under pressure through said rod to a space within said cylinder between said piston and said lower annular member to shift said cylinder downwardly relative to said piston and rod to operate the well device; means for entrapping fluid between said piston and said upper annular member; the annular cross-sectional area of said members being equal; and the external transverse surface of said upper annular member being exposed to the hydrostatic head of fluid within the well bore.
2. In an operating apparatus for well devices:

a first cylinder; a rod secured to said first cylinder; a piston secured to said rod; a second cylinder adapted to be operatively associated with the well device to operate the same and including a sleeve slideable along said piston in sealing engagement therewith and having inwardly directed upper and lower annular members secured to said sleeve on opposite sides of said piston which are slideable along said rod in sealing engagement therewith; means providing a fluid under pressure within said first cylinder; and means for feeding said fluid to a space within said second cylinder between said piston and one of said annular members to shift said second cylinder relative to said rod and first cylinder to operate the well device.

3. In an operating apparatus for well devices to be located in well bores: a first cylinder; a rod secured to said first cylinder; a piston secured to said rod; a second cylinder adapted to be operatively associated with the well device to operate the same and including a sleeve slideable along said piston in sealing engagement therewith and having inwardly directed upper and lower annular members secured to said sleeve on opposite sides of said piston, said members being slideable along said rod in sealing engagement therewith; means providing a fluid under pressure within said first cylinder; means for feeding said fluid to a space within said second cylinder between said piston and said lower annular member to shift said second cylinder downwardly relative to said rod and first cylinder to operate the well device; means for entrapping fluid between said piston and the upper annular member; the external cross-sectional areas of said members being substantially equal, and the external transverse surfaces of said members being exposed to the hydrostatic head of fluid within the well bore.

4. In an operating apparatus for well devices to be located in well bores; a first cylinder; a rod secured to said first cylinder; a piston secured to said rod; a second cylinder adapted to be operatively associated with the well device to operate the same and slideable along said piston in sealing engagement therewith and having upper and lower annular members on opposite sides of said piston slideable along said rod in sealing engagement therewith; means for generating a gas under pressure in said first cylinder; and means for transmitting the force of such gas under pressure to a space within said second cylinder between said piston and one of said annular members to shift said second cylinder relative to said rod and first cylinder to operate the well device.

5. In an operating apparatus for well devices to be located in well bores: a first cylinder; a rod secured to said first cylinder; a piston secured to said rod; a second cylinder adapted to be operatively associated with the well device to operate the same and slideable along said piston in sealing engagement therewith and having upper and lower annular members on opposite sides of said piston slideable along said rod in sealing engagement therewith; means for generating a gas under pressure in said first cylinder; and means for transmitting the force of such gas under pressure to a space within said second cylinder between said piston and one of said annular members to shift said second cylinder relative to said rod and first cylinder to operate the well device; the external cross-sectional areas of said annular members being substantially equal, and the external transverse

surfaces of said annular members being exposed to the hydrostatic head of fluid within the well bore.

6. In an operating apparatus for well devices: a first cylinder; a rod secured to said first cylinder; a first piston in said first cylinder; a second piston secured to said rod; a second cylinder adapted to be operatively associated with the well device to operate the same and slideable along said second piston in sealing engagement therewith and having upper and lower annular members on opposite sides of said second piston slideable along said rod in sealing engagement therewith; means providing a motivating fluid

15 in said first cylinder for action upon said first piston; and means including a fluid for transmitting the force imposed by said motivating fluid on said first piston into a space within said second cylinder between said second piston and one of said annular members to shift said second cylinder and operate the well device.

7. In an operating apparatus for well devices: a first cylinder; a rod secured to said first cylinder; a first piston in said first cylinder; a second piston secured to said rod; a second cylinder adapted to be operatively associated with the well device to operate the same and slideable

20 along said second piston in sealing engagement therewith and having upper and lower annular members on opposite sides of said second piston slideable along said rod in sealing engagement therewith; said rod having a passage therethrough providing communication between said first cylinder and a space within said second cylinder between said second piston and one of said annular members; means providing a motivating fluid in said first cylinder for action upon said first piston; and fluid means in said first cylinder and passage for transmitting the

35 force imposed by said motivating fluid on said first piston to said second piston and said one of said annular members to shift said second cylinder and operate the well device.

8. In an operating apparatus for well devices: a first cylinder; a rod secured to said first cylinder;

45 a first piston in said first cylinder; a second piston secured to said rod; a second cylinder adapted to be operatively associated with the well device to operate the same and slideable along said second piston in sealing engagement therewith and having upper and lower annular members on opposite sides of said second piston slideable along said rod in sealing engagement therewith; said rod having a passage therethrough providing communication between said

50 first cylinder and a space within said second cylinder between said second piston and one of said annular members; means providing a motivating fluid in said first cylinder for action upon said first piston; and fluid means in said first cylinder and passage for transmitting the

55 force imposed by said motivating fluid on said first piston to said second piston and said one of said annular members to shift said second cylinder and operate the well device; the annular cross-sectional areas of said members being substantially equal, and the external transverse surfaces of said annular members being exposed to the hydrostatic head of fluid within the well bore.

9. In an operating apparatus for well devices to be located in well bores: an upper cylinder; a rod secured to and depending from said upper cylinder; an upper piston in said cylinder; a lower piston secured to said rod; a lower cylinder

11

adapted to be operatively associated with the well device to operate the same and slidable along said lower piston in sealing engagement therewith and having upper and lower annular members on opposite sides of said lower piston slidable along said rod in sealing engagement therewith; means providing a motivating fluid in said upper cylinder above said upper piston for downward action upon said upper piston; and means including a fluid for transmitting the force imposed by said motivating fluid on said upper piston into a space within said lower cylinder between said lower piston and said lower annular member to shift said lower cylinder downwardly relative to said rod and upper cylinder to operate the well device.

10. In an operating apparatus for well devices to be located in well bores: an upper cylinder; a rod secured to and depending from said upper cylinder; an upper piston in said cylinder; a lower piston secured to said rod; a lower cylinder adapted to be operatively associated with the well device to operate the same and slidable along said lower piston in sealing engagement therewith and having upper and lower annular members on opposite sides of said lower piston slidable along said rod in sealing engagement therewith; means providing a motivating fluid in said upper cylinder above said upper piston for downward action upon said upper piston; means including a fluid for transmitting the force imposed by said motivating fluid on said upper piston into a space within said lower cylinder between said lower piston and said lower annular member to shift said lower cylinder downwardly relative to said rod and upper cylinder to operate the well device; and means for entrapping fluid between said lower piston and upper annular member; the external annular cross-sectional areas of said members being substantially equal, and the external transverse surfaces of said annular members being exposed to the hydrostatic head of fluid within the well bore.

11. In an operating apparatus for well devices to be located in well bores: an upper cylinder; a rod secured to and depending from said upper cylinder; an upper piston in said upper cylinder; a lower piston secured to said rod; a lower cylinder adapted to be operatively associated with the well device to operate the same and slidable along said lower piston in sealing engagement therewith and having upper and lower annular members on opposite sides of said lower piston slidable along said rod in sealing engagement therewith; said rod having a passage therein establishing communication between said upper cylinder and a space within said lower cylinder between said lower piston and said lower annular member; means providing a motivating fluid in said upper cylinder for downward action upon said upper piston; fluid means in said upper cylinder and passage for transmitting the force of said upper piston into said space between said lower piston and lower annular member to shift said lower cylinder to operate the well device; means for entrapping fluid between said lower piston and upper member; the external annular cross-sectional areas of said members being substantially equal; and the external transverse surfaces of said members being exposed to the hydrostatic head of fluid within the well bore.

12. In an operating apparatus for well devices to be located in well bores: an upper cylinder; a rod secured to and depending from said upper cylinder; an upper piston in said upper cylinder;

12

a lower piston secured to said rod; a lower cylinder adapted to be operatively associated with the well device to operate the same and slidable along said lower piston in sealing engagement therewith and having upper and lower annular members on opposite sides of said lower piston slidable along said rod in sealing engagement therewith; said rod having a passage therein establishing communication between said upper cylinder and a space within said lower cylinder between said lower piston and said lower annular member; means providing a motivating fluid in said upper cylinder for downward action upon said upper piston; and fluid means in said upper cylinder and passage for transmitting the force imposed by said motivating fluid on said upper piston into said space between said lower piston and lower annular member to shift said lower cylinder and operate the well device.

13. In an operating apparatus for well devices to be located in well bores: an upper cylinder; a rod secured to and depending from said upper cylinder; an upper piston in said upper cylinder; a lower piston secured to said rod; a lower cylinder adapted to be operatively associated with the well device to operate the same and slidable along said lower piston in sealing engagement therewith and having upper and lower annular members on opposite sides of said lower piston slidable along said rod in sealing engagement therewith; said rod having a passage therein establishing communication between said upper cylinder and a space within said lower cylinder between said lower piston and said lower annular member, means providing a motivating fluid in said upper cylinder for downward action upon said upper piston; fluid means in said upper cylinder, passage and space within said lower cylinder for transmitting the force imposed by said motivating fluid on said upper piston into said space between said lower piston and lower annular member to shift said lower cylinder and operate the well device; and means providing an orifice in said passage.

14. In mechanism of the character described: a well device to be operated in a well bore; an apparatus operatively connected to said device to operate the same, said apparatus including a cylinder having longitudinally spaced annular members, piston means slidable relatively along said cylinder in sealing engagement therewith and with said annular members between said members, means for feeding fluid under pressure into said cylinder between said piston means and one of said members to shift said cylinder and operate the well device, means for entrapping fluid in said cylinder between said piston means and the other member, the annular cross-sectional areas of said members being equal.

15. In mechanism of the character described: a well device to be operated in a well bore; an apparatus operatively connected to said well device to operate the same, said apparatus including a longitudinally extending rod, a piston secured to said rod, a cylinder slidable along said piston in sealing engagement therewith and having upper and lower annular members on opposite sides of said piston slidable along said rod in sealing engagement therewith, means for feeding fluid under pressure through said rod to a space within said cylinder between said piston and one of said members to shift said cylinder to operate said well device, means for entrapping fluid between said piston and the other member, the annular cross-sectional areas of said mem-

13

bers being equal, and the external transverse surface of said other annular member being exposed to the hydrostatic head of fluid within the well bore.

16. In mechanism of the character described: a well device to be operated in a well bore; a first cylinder; a rod secured to said first cylinder and well device; a piston secured to said rod; a second cylinder slidable along said piston in sealing engagement therewith and having upper and lower annular members on opposite sides of said piston slidable along said rod in sealing engagement therewith; means providing a motivating fluid under pressure within said first cylinder; means for feeding said fluid to a space within said second cylinder between said piston and said lower annular member to shift said second cylinder downwardly relative to said rod and first cylinder to operate said well device; means for entrapping fluid between said piston and the upper annular member; the external cross-sectional areas of said members being substantially equal, and the external transverse surfaces of said members being exposed to the hydrostatic head of fluid within the well bore.

17. In mechanism of the character described: a body; normally retracted means on said body adapted to be expanded laterally; a first cylinder; a rod secured to said first cylinder and body; a piston secured to said rod; a second cylinder slidable along said piston in sealing engagement therewith and having upper and lower annular members on opposite sides of said piston slidable along said rod in sealing engagement therewith; means providing a motivating fluid under pressure within said first cylinder; means for feeding said fluid to a space within said second cylinder between said piston and said lower annular member to shift said cylinder downwardly relative to said rod and first cylinder to expand said normally retracted means laterally; means for entrapping fluid between said piston and the upper annular member; the external cross-sec-

14

tional areas of said members being substantially equal, and the external transverse surfaces of said members being exposed to the hydrostatic head of fluid within the well bore.

18. In mechanism of the character described: a well device to be operated in a well bore; an apparatus operatively connected to said device to operate the same, said apparatus including a first cylinder, a rod secured to said first cylinder and well device, a piston secured to said rod, a second cylinder slidable along said piston in sealing engagement therewith and having upper and lower annular members on opposite sides of said piston slidable along said rod in sealing engagement therewith, means for generating a gas under pressure in said first cylinder, and means for transmitting the force of such gas under pressure to a space within said second cylinder between said piston and one of said annular members to shift said second cylinder relative to said rod and first cylinder to operate said well device, the external cross-sectional areas of said annular members being substantially equal, and the external transverse surfaces of said annular members being exposed to the hydrostatic head of fluid within the well bore.
